United States Patent Office.

STEPHAN EICH, OF EAST TOLEDO, OHIO.

Design No. 3,696, dated October 5, 1869.

DESIGN FOR DOOR-KNOB.

The Schedule referred to in these Letters Patent and making part of the same.

To all whom it may concern:

Be it known that I, STEPHAN EICH, of East Toledo, in the county of Lucas, and State of Ohio, have invented a new and original Design for Door-Knob; and I do hereby declare that the following is a full, clear, and exact description thereof, which will enable others skilled in the art to make and use the same, reference being had to the accompanying drawings, forming part of this specification.

This invention relates to a new and ornamental design for the form of door-knobs.

Figure 1 represents a front elevation of a door-knob formed according to my improved design, and

Figure 2 represents a section through the same.

Instead of forming these knobs, as heretofore done, with circular enlargements at the parts where they are taken hold of by the hands for turning them, I propose to make them considerably longer one way than the other—that is to say, with a long longitudinal axis, and short transverse axis, and with sides representing two curves opposed to each other, one a convex curve, A, and the other a concave curve, B; and these curves,

I reverse on the opposite sides, the convex curve, at one end, being opposite the concave curve at the other, thereby forming points, D, diagonally opposed to each other.

The corners of the front face E are suitably carved, to present the most ornamental appearance, and to facilitate holding the knobs in the hand.

These knobs, I propose to secure to the spindles in the usual way; or the rods of the spindles may be enlarged, as at F, and provided with axial screw-holes, into which screws, fitted to the knobs, or screwed through them, may be screwed, for connecting them.

Having thus described my invention, I claim as new, and desire to secure by Letters Patent—

The design for door-knobs herein set forth and shown.

STEPHAN EICH.
